(57) **CLAIM**

I claim the insulated ground tent, as shown.

DESCRIPTION

FIG. 1 shows a top and side perspective view of an insulated ground tent, the bottom and side perspective view being a mirror image thereof.

FIG. 2 shows a left side elevation view thereof, sixty degree elevational offsets being identical.

FIG. 3 shows a right side elevation view thereof, sixty degree elevational offsets being identical.

FIG. 4 shows a front side elevation view, sixth degree elevational offsets being identical.

FIG. 5 shows a top plan view thereof; and,

FIG. 6 shows a bottom plan view thereof.

The stippling shown throughout the figure views is a surface shading which represents a contrast in appearance from non-stippled surfaces.
